INVENTOR
A. J. Cook

UNITED STATES PATENT OFFICE.

ADONIRAM J. COOK, OF WESTERLO, NEW YORK.

RAIL ANTICREEP AND ANTISPREAD ANCHOR.

Application filed January 22, 1929. Serial No. 335,721.

As is well known by those engaged in railroad operation, the general causes of rail creeping are: the wave motion of the track under the alternate application and release 5 of a rolling load; the application of the brake, especially when the wheels slide; curvature of the track when the velocity of the train is greater or less than the velocity for which the outer rail is elevated; and descending 10 grades. Rails creep also excessively on bridges.

The main object of my invention is the provision of a device which when several thereof are combined with track rails and 15 cross ties will prevent the creeping or longitudinal movement of the rails relative to the ties under traffic. Its function is to hold the rail in a fixed position relative to the tie so the force which causes creeping will be transmitted through both the rail and tie to the 20 track ballast.

Another object is the provision of a rail anchor which shall perform the additional function of preventing the sideways movement of the rail relatively to the tie, or the 25 spread of the rails.

The invention consists in certain novelties of construction and in the combination of parts as herein set forth and claimed.

30 The accompanying drawing illustrates an example of the embodiment of the invention, the parts being constructed and combined according to the best mode of procedure I have so far devised for the purpose.

35 Figure 1 is a view in perspective of part of a track tie and part of a rail, showing also my improved rail anti-creep and anti-spread device in position as applied to the rail and tie.

40 Figure 2 is a perspective view of the device as it appears prior to its application to the rail and tie.

Figure 3 is an end view of the lower part of Figure 1, showing the rail in section and 45 the device in side elevation.

Referring to the figures, the numeral 5 designates a track tie of the usual type; 6, the rail head; 7, the web of the rail; 8, 8 are the base flanges, and 9, 9 the usual spikes 50 which secure the rail to the tie. The device consists of a blank of metal, shown by Figure 2, preferably of soft steel or malleable iron, bent or fashioned to the shape shown by Figures 1 and 3.

55 The jaw 15 is integral with the shank 10.

At the end opposite the jaw 15 is an upwardly projecting lug 11 with two seats for one flange of the base of the rail.

The auxiliary jaw 14 is formed by bending the metal back of jaw 15 at 12 upon itself 60 through an arc of about 180° to a curved shape and substantially parallel with the jaw 15 so the end of the jaw 14 will preferably engage the side surface of the jaw 15.

The strap end 17 has a hole 18 at the end 65 to receive an anchoring spike 19. This strap is first bent on the line 16 to a vertical position at right angles to the length of the shank 10 of the blank, and then bent on the line 20 at right angles to the vertical plane 70 of the shank so that, when the device is applied edgewise beneath the flanges of the rail and in frictional contact with one vertical surface of the tie, the under surface of the strap will lap over and frictionally engage 75 the top surface of the edge of the tie, as shown.

Figures 1 and 3 illustrate the device applied to the rail and tie, the same being forced to its proper position and the strap 80 secured to the top surface of the tie by the spike 19.

The edge of one of the flanges of the rail will engage one or the other of the seats on the upwardly projecting lug 11, depending 85 upon the distance the body of the device is forced beneath the rail base.

It will be seen that the free end of the curved auxiliary jaw 14 bears against the side of the main jaw 15 and also upon the 90 top surface of the rail flange, whereby additional strength and increased bearing surface are secured when the anchor is driven to position.

The auxiliary jaw as the lower edge is in 95 a plane below the lower oblique edge of jaw 15 not only increases the grip on the flange, but also has a tendency when driven on to tilt the main jaw and produce a twisting gripping effect.

Bending one end of the blank on the lines 16 and 20 brings the strap 17 to a position where it lies flat upon the top surface of the tie. When spiked to the tie the strap holds the anchor against the side of the tie under 105 all conditions of service, and at the same time prevents the side movement of the rail relatively to the tie; or, in other words, prevents the spread of the rails.

From the foregoing it will be clear that I 110

have produced not only an efficient rail anchor for holding the rail against longitudinal movement relatively to the tie, but also a device having the additional function 5 of preventing the spread of the rails.

A plurality of my improved devices will in use anchor the rails to the ties so the rails will not creep, and at the same time they will prevent the displacement of either rail or 10 both rails relatively to the length of the ties; in other words, prevent the spreading of the rails.

What I claim is:

1. A combined rail anti-creep and anti-15 spread anchor comprising an anti-creep device adapted to be located beneath a rail and bear against one side of a tie, and having at one end thereof a jaw adapted to overlap a rail flange and also adjacent said 20 jaw an integral projection for attachment to a tie.

2. The subject-matter of claim 1 wherein said device has at one end thereof intermediate its length two jaws adapted to overlap 25 the flange of a rail and also adjacent said jaws an integral projection for attachment to a tie.

3. A combined rail anti-creep and anti-30 spread anchor comprising a shank, a projection at the free end of the shank adapted to engage one flange of a rail, a jaw adjacent the opposite end of the shank and integral therewith adapted to lap over and engage the other flange of a rail, and a strap ad-

jacent the said jaw disposed at right angles 35 to the plane of the shank and adapted to be secured to a tie.

4. The subject-matter of claim 3 wherein the said strap is integral with the shank and bent from a position in line with the shank 40 on the lines 16 and 20 so the strap will project at an angle to the vertical plane of the shank.

5. A rail anti-creep and anti-spread anchor having means for engaging the 45 flanges of a rail, and a strap integral with the means for engaging the flanges of a rail, said strap being bent on the oblique line 16 and upon the line 20 so as to project at an angle to the length of said means and thus 50 be adapted to engage a tie.

6. A rail anti-creep and anti-spread anchor having a shank with a projecting lug 11 at its free end and intermediate its ends a jaw adapted to overlap a flange of 55 a rail, and a strap, as 17, projecting at right angles to the vertical plane of the shank of the anchor and adapted to be secured to a tie.

7. The combination with the vertical surface of a track tie, of an anti-creep and anti-spread anchor having an integral jaw intermediate its length adapted to be driven 60 onto one flange of a rail and a projection at right angles to the jaw of the anchor and 65 secured to the tie by a spike.

ADONIRAM J. COOK.
